UNITED STATES PATENT OFFICE.

CHARLES D. McDONALD, OF CHICAGO, ILLINOIS.

DIE-PRESS MECHANISM.

1,272,481.

Specification of Letters Patent. Patented July 16, 1918.

Application filed April 23, 1917. Serial No. 164,025.

To all whom it may concern:

Be it known that I, CHARLES D. McDONALD, a citizen of the United States, residing at Chicago, in the county of Cook and State of Illinois, have invented certain new and useful Improvements in Die-Press Mechanism, of which the following is a specification.

The present invention relates principally to means for feeding the work across the surface of the fixed die of an automatic die-press, and for centering the work with respect to such die previous to each cutting operation.

One of the objects of the invention is to provide a gage or centering member which will position the work with respect to the fixed die in such manner as to have the near side of one cut coincident with the far side of the next adjacent cut, thereby eliminating any waste of metal by reason of the cuts being separated or spaced apart from one another and a web of material left between the cuts.

A further object of the invention is to lift or remove this gage member out of the path of travel of the work after the last cut has been made, so as to allow an ejection of the waste from the machine.

A further object of the invention is to provide means which will exert a continuous pulling pressure upon the work to drag it across the die, and to have this pulling force of such degree that when the work is arrested by contact with the gage member, the said pulling means will be capable of a slippage upon the work.

A further object of the invention is to provide means in front for initially feeding the work across the die and into position to be operated upon by secondary feed means located beyond the die.

A further object of the invention is to utilize a reciprocating feed bar for the initial feeding operation and to provide compensating means between this feed bar and its actuating member, so as to eliminate bending or mutilating the work in case of any excess movement of the feed bar.

The invention further consists in the features of construction and combination of parts hereinafter described and claimed.

In the drawings:

Figure 1 is a front view of an automatic die-press equipped with the devices of the present invention;

Fig. 2, a detail plan view showing the feed means and gage member;

Fig. 3, a detail showing the work positioned for the first cut;

Fig. 4, a detail showing the work positioned for the second cut and the work advanced into the bite of the rear feed rolls;

Fig. 5, an elevation showing a side view of the movable die and ejector ring;

Fig. 6, a bottom face view of said ejector ring;

Fig. 7, a vertical section through the compensating connection between the feed bar and its actuating means, taken on line 7—7 of Fig. 1;

Fig. 8, a view of the waste strip of work which remains after the cutting operation is complete; and

Fig. 9, a detail section on line 9—9 of Fig. 1, looking in the direction of the arrows.

Referring now to the drawings, and particularly to Fig. 1, the invention is shown as applied to an automatic press body 9 of any suitable size and arrangement. A main driving shaft 10 actuates, through a suitable connection, a movable die 11, which cooperates with a fixed die 12 to perform the cutting operation. Located upon the far side 13 of the die 12 is a finger or gage 14, the edge of which is coincident with the cutting edge of the die, as will be apparent from Figs. 1 and 2.

In the specification and claims, the words "near" and "far" will be employed to describe different sides of the die, the near side 13^a of the die being the side which the work crosses first in passing across the die, and the far side 13 being that side which the work crosses last in passing across the die. That is, the work in passing across the die will move from the near side toward the far side. These terms, however, are descriptive and are used because it is thought they will expedite a clear understanding of the mechanism, and are not intended as words of limitation in any other respect.

The gage or finger 14 is pivotally mounted upon a rod 15, to which is connected a crank 16 joined in turn to the end of an arm 17, pivoted upon a stub shaft or pin 18. This stub shaft 18 is rocked by the movements of a member 19, which in turn is actuated by a bent stem 20 extending from a rod 21, which rod is rocked through the movements of an arm 22. The upper end of this

arm 22 lies within a cam groove formed in the side face of a gear 24 carried by a stub shaft 24^a. The gear 24 is driven by a gear 24^c on a stub shaft 24^d carried by an arm 24^e. The shaft 24^d also carries a gear 24^e, which meshes with a gear 24^f on a shaft 24^h, which carries the disk 46 hereinafter referred to. The gear 24^f is driven by a gear 24^h on a shaft 24ⁱ, to which power is applied from the main drive shaft. The shaft 24ⁱ revolves once for each revolution of the main drive shaft. The gear connection to the shaft 24^a revolves the latter once for each predetermined number of revolutions of the drive shaft, such number of revolutions depending on the ratios existing between the gears 24ⁱ, 24^f, 24^e, 24^c and 24. This ratio is such as to cause the cam groove 24^b to act and move the cross rod 21 immediately after the last cut has been made from the strip of work, thus operating the gage 14 to lift it over the web 23 on the tail end of the work, as will be more fully hereinafter brought out.

Located, in the construction shown, beyond the die are feed rolls 25, suitably geared together and driven by a belt 26 from a groove wheel 27, actuated by the main drive shaft. These feed rolls rotate continuously, and when the work has been placed between the bite of said rolls, a pulling action is constantly exerted, tending to pull the work across the die. The degree of pulling power of the rolls is such as to enable a slippage of the rolls with respect to the surface of the work under certain conditions, the purpose of which will hereinafter appear.

Located in front of the die, in the construction shown, is a reciprocating feed bar 28, having, as shown, a forward tooth 29 and a rear tooth 30. This feed bar is connected by a suitable stem or other connecting member 31 to a block 32, which is mounted within a slot 33 on one end of a feed bar actuating member 34. Within the slot is positioned a spring 35 pressing against the block and tending to normally keep the said block at one end of said slot. The above constitutes a compensating means between the feed bar and its actuating member, the function of which will subsequently be described.

The movable die 11 carries a stripper ring 35 working against a spring 36, and this stripper ring is provided with a cutaway portion or recess 37 to enable it to straddle the finger or gage 14 when the movable die descends.

In the operation of the machine, the work is first advanced by the feed bar 28, and through the operation of the forward tooth 29. This tooth acts to feed the work into the position shown in Fig. 3—that is, across the fixed die and into engagement with the gage 14—and when so brought to position, the movable die descends and cuts out a blank. The far side of this first cut, indicated

by the numeral 39 in Fig. 3, is coincident with the front edge of the strip, and hence after this cut has been made, there is an opening at said edge between the waste work upon each side of the strip, as will be apparent from Fig. 8. After this cut has been made, the feed bar again acts, and the rear tooth 30 feeds the work forward until the gage finger 14 strikes the edge 40 upon the near side of the cut last made. 75

It will be remembered that there was an opening produced upon the far side of the cut, as indicated by the numeral 39. With such an opening, when the work is fed forward, the gage finger 14 will pass through 80 the opening and the work will continue to travel forward until the gage strikes the edge 40 on the near side of the cut. This brings the work to a stop, and as the gage finger 14 is coincident with the far side of 85 the die, it will follow that the near side of the last cut will be brought to rest at a point coincident with the far side of the die. By this time the die has again acted and will cut out the blank as indicated by the numeral 41 in Fig. 4. 90

The second movement of the reciprocating feed bar brings the edges of the waste work up into the grip of the feed rolls 25, and these feed rolls are therefore at this time exerting a pull tending to drag the work across the die. After the second cut has been made, there will be an opening formed similar to the opening 39, due to the coincidence of the adjoining portions of the lines 100 of cut made by the first and second cutting operations; and after the movable die has receded from engagement with the work, the feed rolls will immediately act to drag the work toward them. The gage finger 14 will 105 pass through the second opening, indicated by the numeral 39 in Fig. 8, and the work will continue to advance under the influence of the feed rolls until the gage finger 14 strikes the near side of the last cut. This 110 will check the movement of the work, and as the pulling action of the feed rolls is less than the retarding action of the gage finger, these rolls will slip upon the waste portion of the work after the gage finger has 115 encountered the work. Thus, the movement of the work will be stopped and the work again centered, whereby the near side of the last cut will be coincident with the far side of the next cut, and the strip cut in a manner to leave an opening 39 centrally thereof, as has been explained. 120

After the movable die has been retracted from the fixed die, the feed rolls again act to pull the work forward and the operation 125 aforesaid is repeated. In this manner the cuts are made in the work, whereby merely the side edges are left as scrap, as will be understood from Fig. 8. It will be in most cases a practical impossibility to cut 130

the blanks with sufficient accuracy so as to make the last cut terminate exactly on the rear edge 43 of the blank, and in practically all cases there will be a narrow web left at 5 this rear end.

If the gage finger 14 remained stationary at all times, this rear web would catch against said finger and prevent the ejection of the waste from the machine. 10 Therefore, at the completion of the last cut, the cam 24 acts, through the roller 23, to move the arm 22, rock the shaft 21, raise the bent finger 20, swing upward the member 19, rocking the stub shaft 18 carrying 15 the arm 17 in the direction of the arrow (Fig. 1), which moves the crank 16 in the direction of the arrow, and will swing the finger 14 upward and out of the path of travel of the work, whereupon the feed rolls 20 25 will act to draw the waste work entirely out of the machine and eject it into the scrap heap.

In feeding the work by the reciprocating feed bar, it may happen, for some reason 25 or other, that the bar would give a greater movement to the work than would be necessary to bring it up against the gage finger 14, and if it struck said finger 14 before the limit of movement of the feed bar was 30 reached, there would be a buckling and bending of the work at one point or another, which would mutilate the work so that it would not feed freely through the machine. I overcome this possible difficulty by employing a compensating or yielding connection between the feed bar and its actuating member 34. This actuating member is reciprocated by a bell crank lever 44 connected to a rod 45. The end of the rod 45 lies in 35 a groove formed in a disk 46 mounted on the shaft 24^a. Reference is made to Patent No. 970,092 granted September 13, 1910, to C. D. McDonald, for automatic die-press, relative to the operation of this disk 46 and 40 also relative to the changing of time of the shaft 24^a.

Should it happen that an excess movement be given the actuating member 34 and the feed bar so moved as to cause the work 45 to strike the gage finger 14 previous to the termination of the movement of the feed bar, the striking of the work against the gage finger 14 will arrest the movement of the feed bar and place a back pressure 50 thereon, which will be communicated to the block 32; and this block, having encountered a resistance to its movement with the actuating member 34, will remain still and the spring 33 will be compressed, which will 55 allow of the actuating member 34 completing its movement, but without imparting excess movement to the finger bar. In this manner any undesirable conditions resulting from an abnormal movement of the feed bar 60 or a premature engagement of the work 65

with the gage finger 14 will be eliminated, and the danger of mutilation of the work avoided.

I claim:

1. In an automatic die-press, the combination of a fixed die member, a movable die member, a gage positioned on the far side of the fixed die in alignment with the cutting edge thereof, said gage acting to center the work so that the far side of one cut comes into alignment with the near side of the preceding cut and the work entirely cut away at a point centrally between the cuts, said gage being positioned in alignment with said cut-away parts, whereby the work may be fed past said gage without movement of the latter, means for automatically moving the gage after the last cut has been made out of the path of travel of the work to enable the web at the end of the work to pass by the gage and the scrap work ejected from the machine, and means for feeding the work through the machine and out therefrom, substantially as described.

2. In an automatic die-press, the combination of a fixed die member, a movable die member, a gage in the form of a pivoted finger positioned on the far side of the fixed die in alignment with the cutting edge, said gage acting to center the work so that the far side of one cut comes into alignment with the near side of the preceding cut and the work entirely cut away at a point centrally between the cuts, said gage being positioned in alignment with said cut-away parts, whereby the work may be fed past said gage without movement of the latter, means for automatically rocking said finger after the last cut has been made to move it out of the path of travel of the work and enable the web at the end of the work to pass by said gage and the scrap work ejected from the machine, and means for feeding the work through the machine and out therefrom, substantially as described.

3. In an automatic die-press, the combination of a fixed die member, a movable die member, a gage in the form of a pivoted finger positioned on the far side of the fixed die in alignment with the cutting edge, said gage acting to center the work so that the far side of one cut comes into alignment with the near side of the preceding cut and the work entirely cut away at a point centrally between the cuts, said gage being positioned in alignment with said cut-away parts, whereby the work may be fed past said gage without movement of the latter, a series of links and levers operatively connected to said finger, and means acting automatically when a predetermined number of cuts have been made to move said links and levers and raise the finger to enable the web at the end of the work to pass by the gage and the scrap work ejected from the machine, and means for

feeding the work through the machine and out therefrom, substantially as described.

4. In an automatic die-press, the combination of a fixed die member, a movable die member, a gage positioned on the far side of the fixed die in alinement with the cutting edge, said gage acting to center the work so that the far side of one cut comes into alinement with the near side of the preceding cut and the work entirely cut away at a point centrally between the cuts, said gage being positioned in alinement with said cut-away parts, whereby the work may be fed past said gage without movement of the latter, reciprocating feed means for moving the work across the fixed die member and into contact with the gage, and resilient means interposed in the feed means to allow said feed means to give in case the work is brought into contact with the gage prior to the completion of the stroke of the feed member, whereby buckling of the work by pressure of the feed means after the work has come into contact with the gage is prevented, substantially as described.

5. In an automatic die-press, the combination of a fixed die member, a movable die member, a gage member adapted to engage

and center the work prior to each cutting operation, reciprocating feed means for moving the work across the fixed die member and through the machine, a resilient means interposed in the feed means to allow said feed means to give in case the work is brought into contact with the gage prior to the completion of the stroke of the feed means, whereby buckling of the work by pressure of the feed means after the work has been brought into contact with the gage is prevented, substantially as described. 40

6. In an automatic die-press, the combination of a fixed die member, a movable die member, a gage member adapted to contact the work and center it prior to each cutting operation, means for feeding the work 45 through the machine, comprising a reciprocating feed bar, an actuating member for said bar, and a resilient connection between the actuating member and feed bar allowing the bar to give in case the work is brought into contact with the gage prior to the completion of the stroke of said bar, whereby buckling of the work by pressure of the feed means after the work has contacted the gage is prevented, substantially as described. 50

CHARLES D. McDONALD.
